UNITED STATES PATENT OFFICE.

HERBERT L. ROBERTS, OF TORONTO, ONTARIO, CANADA, ASSIGNOR TO BUSINESS SYSTEMS, LIMITED, OF TORONTO, ONTARIO, CANADA, A CORPORATION OF CANADA.

AUTOGRAPHIC REGISTER.

1,422,132.

Specification of Letters Patent. Patented July 11, 1922.

Application filed September 24, 1918. Serial No. 255,481.

To all whom it may concern:

Be it known that I, HERBERT L. ROBERTS, a subject of the King of England, residing at Toronto, in the Province of Ontario, Dominion of Canada, have invented certain new and useful Improvements in Auto-graphic Registers, of which the following is a full and clear specification.

The present invention relates to improvements in autographic registers of the type in which a plurality of webs of paper containing printed forms, such as for sales slips, and longitudinally spaced pairs of registering perforations are periodically engaged by aligning pins to relatively register the superposed forms at the completion of each recording and feeding operation, so as to insure the detachment of slips of uniform length corresponding properly with the printed forms contained thereon.

The main feature of the present invention comprises a novel form of manually operated registering and aligning device. The aligning device is preferably arranged to be actuated simultaneously with a feed release and a check severing device, so that a single manual operation severs the duplicate checks, releases the grip of the feed devices and properly aligns the webs for the next recording operation. The web feeding mechanism may be of any suitable form, but I prefer to employ a feed mechanism of the type that feeds a predetermined length of web which will feed from the machine the slips of approximately the required length and place the succeeding web perforations within range of the registering and aligning pins which correct the inaccuracies of the feed after each operation.

In order that the invention may be fully understood it will first be described with reference to the accompanying drawings and the novel features afterwards pointed out more particularly in the annexed claims:

In said drawings,

Figure 1 is a side elevation of an autographic register embodying the present invention;

Figure 2 is a plan view of the same;

Figure 3 is an end elevation of the delivery end of the machine, parts being shown in section;

Figure 4 is a longitudinal sectional view of the main operative parts of the machine.

For purposes of illustration the present

invention is shown in the accompanying drawings applied to a machine frame, having the same general structure as the machine of my application Serial No. 247,039, filed in the U. S. Patent Office July 27th, 1918, but it will be understood that these structural features are not essential to the present invention.

In the embodiment of the present invention, shown in the accompanying drawings, the machine is built up upon the usual side frames 1 and 2, connected by strengthening cross rods or tie bars, such as shown at 3 and by the operating parts hereinafter referred to. 5 is a table frame pivotally mounted at its rear end upon a rod 6, mounted in the upper edges of side frames 1 and 2 and formed with downwardly presented side flanges that snugly fit over the upper edges of the side frames 1 and 2 when the table is in lowered operative position. The rear end of the table is cut away and mounted in this cutaway portion are downwardly presented bracket flanges 14 and 15, formed with inclined slots 16, in which are freely mounted the journal ends of gravity idler rolls 20. These rolls 20 serve the double function of guiding the webs of paper from the supply rolls (presently referred to) to the writing table, and providing automatic means for moving the webs rearwardly over the table when the feed mechanism releases them for the purpose hereinafter explained. The number of idler rolls 20 depends upon the number of webs that are to be handled in the machine. The accompanying drawings show four such rolls.

The previously printed and properly perforated webs or sheets are mounted in roll form as commonly practiced in this art. The rolls of prepared webs, preferably upon tubular spindles, such as is usually made of paper board, are mounted between bearing cones arranged in pairs. Each pair of bearing cones comprises a stationary flanged head 25, mounted upon a rigid pin or lug, in one side frame and a movably mounted flanged head 26, mounted upon the inner end of a sliding rotating pin 27, extending through bearing 28 in the opposite side frame and supporting an expansion spring 29 between the head 26 and the side frame for holding the head yieldingly in engagement with the tubular roll spindle. These spring pressed rotating bearings for the

rolls cause the rolls to be pressed against the stationary bearing heads with sufficient pressure to properly retard the feeding movement and since all of the rolls are pressed 5 toward the same side of the machine and are supported by the same form of devices it will be seen that the side edges of the superposed webs of paper will be properly aligned.

Secured to the side flange of table 5 at 10 the right, is a suitably mounted support 40 for a roll of carbon sheets used in manifolding in the well known way. The details of this part of the construction are fully set forth in my above-named application.

15 60 is a flanged cover plate pivotally mounted upon the rod 6 and formed with downwardly presented side flanges adapted to fit over the side flange of table 5 at one side and the carbon roll support at the opposite side.

20 This cover plate forms a top housing for the carbon sheets and a marginal housing for the superposed webs of papers, the plate being centrally cut out as shown at 61 to expose the central zones of the successive register blanks 25 of the topmost web.

Mounted between the side frames at their forward or delivery ends is a suitable frame consisting of side plates 75 braced by suitable tie plates in which is mounted the web 30 feeding and aligning mechanisms which will now be described.

The upper feed roller 80 is journaled in the upright side members 75 just above the plane of the feed of the paper webs from the 35 writing table. This upper roll 80 is formed with annular feed ribs or collars 81 a short distance from its ends.

Secured to the protecting journal end of roll 80 is a driving pinion 85 which is in 40 constant mesh with a large gear 86 journaled upon a stub shaft 87 properly mounted in side frame 2. A large ratchet wheel 88 is journaled upon shaft 87 alongside of gear 86 to which it is rigidly secured at its hub.

45 90 is a crank disk freely journaled upon stub shaft 87 alongside ratchet wheel 88 and carrying an operating crank handle 91 and a pawl or dog 92 which is held by a spring or other suitable device (not shown) in 50 operative relation to the ratchet wheel 88 which it drives. The crank disk 90 is engaged adjacent to its hub by one end of a torsion spring 95 which is coiled upon stub shaft 87, and rigidly held at its opposite end 55 by a collar or washer 96 clamped upon shaft 87 by nut 97. The spring 95 holds the crank disk in its retracted position and returns it to that position automatically after each feeding movement when the operator re-

60 moves his hand from the crank. 93 is a housing for spring 95. 94 is a stop suitably mounted on the machine frame in position to engage the heel of dog 92 or any other projection on disk 90 to limit the return 65 movement thereof.

100 is an angular stop arm clamped upon the end of stub shaft 87 between collar 96 and nut 97 and projecting into the path of crank 91 to limit the forward feed movement of crank disk 90. The arm 100 is adjustably mounted so as to provide a feed stroke of the desired length.

110 is the lower feed roller freely journaled at its ends in a pivotally mounted carrying frame formed of angular side 75 plates 111 joined by an angular tie plate 112 and pivotally mounted upon frame plates 75 at 113. Tension springs 115 connect the downwardly presented arms of side plates 111 with a tie rod 116 extending between main side frames 1 and 2. These springs normally maintain lower feed roller 110 in yielding peripheral engagement with the feed collars 81 of the upper feed roller. A lug 117 projects from the angular tie plate 80 112 near its middle to be engaged by the cutter bar for the purpose hereinafter explained. Feed rollers 80 and 110 are geared together as indicated by dotted lines at 118 so as to rotate in unison, the roller 110 being 90 driven by the roller 80.

A transversely extending housing plate 120 extends over the feed rollers 80 and 110 between side plates 75. Centrally mounted upon plate 120 is a rigid angular bracket 95 125 formed with a vertical guide opening in line with a similar opening in plate 120, and freely mounted in said openings is a tubular stem 130 rigidly attached to and extending up from a combined clamp bar and cutter carrier 135 of U-shaped cross section. This U-shaped bar 135 is arranged to reciprocate vertically between plates 75 toward and away from the plane of feed of the webs. Corner plates 136 guide the bar 135 at its ends. A cutter bar 140 (preferably formed with a serrated lower cutting edge) is freely mounted in the U-shaped bar 135 and is completely housed thereby. Cutter 140 is pivoted to bar 135 at one end 141 to 105 afford an independent downward movement on bar 135 for the purpose presently explained. A guide rod 142 is suitably attached to cutter bar 140 and extends therefrom up through the tubular bar 130 and 110 has secured to its upper end a hand-pressure plate 145. Two concentric expansion coil springs, 150 and 151 are confined beneath hand plate 145. The inner spring 150 surrounds rod 142 and is confined between plate 145 and the upper end of tubular stem 130, thereby yieldingly holding cutter 140 in the housing pressure bar 135, and the spring 151 surrounds the upper end of stem 130 and is confined between plate 145 and bracket 125, 115 for the purpose of yieldingly supporting pressure bar 135 and cutter bar 140 in raised position in the frame.

The tie plate 77 is preferably of angular cross section having a horizontal web ar- 130

ranged in the plane of feed at the delivery end of the machine. The horizontal web of plate 77 is formed with a vertical slot directly beneath the cutter bar 140 into which 5 said cutter bar projects when operated for cutting off slips. The U-shaped presser bar 135 engages the paper webs against the horizontal portion of plate 77 in front and rear of the path of cutter 140 to effectively hold 10 the webs when the cut-off is made.

Arranged beneath the path of paper webs between the tableplate 5 and feed rolls 80, 110, are the aligning and registering members 150 which have conical upper ends, and 15 are spaced transversely to simultaneously engage the pairs of openings in the superposed webs extending over the table plate 5. The members 150 are mounted upon the upper ends of arms 151 of an upright U-shaped 20 rod or frame 152 loosely mounted in the flanged guide plates 153 secured upon tie rod 116.

155 is a horizontally presented U-shaped rock arm freely journaled upon rod 116 in 25 the central longitudinal plane of the machine and formed in its rearwardly presented arms with the horizontal slots 156 which engage the U-shaped rod 152.

A vertical rod 160 passes through and 30 engages the lug 117 of the lower feed roller frame, and is formed with an angular lower end 161 which engages an opening in the U-shaped rock arm 155. The rod 160 is for the purpose of simultaneously operating the 35 roller frame and the registering cones.

In operation, it will be understood that the recording and manifolding are accomplished in the well known manner. The stop arm 100 is set to limit the feed of superposed 40 webs to approximately the web length between two sets of register openings. When a record has been made the operator rotates the crank disk 90 until its movement is arrested by the stop arm, with the result that 45 a certain length of the superposed webs will be fed through rollers 80 and 110 and will project beyond plate 77. Hand plate 145 is next pressed downwardly, clamping the superposed webs in front and rear of the path 50 of the knife, and forcing cutter 140 through the webs to sever the projecting manifold slips or checks. The cutter 140, moving downwardly, engages and depresses rod 160 to cause lower feed roller to move away from 55 the upper roller and free the webs at the instant that the register cones are moved up into engagement with the perforations of the superposed webs and cause them to be relatively shifted into proper position.

60 The take up rollers 20 above referred to may be employed in the improved machine but they are not essential to the present invention, which in its broadest sense comprehends the release of the webs from the feed 65 mechanism and the shifting of the freed

webs into registered position by the action of the registering members.

Further features of the invention include the simultaneous operation of the feed freeing and registering devices, the combination 70 therewith of the check severing device; the combination of a predetermined web length feed with the registering means; and the specific construction of the several mechanisms for accomplishing the results described. 75

The improved machine is of simple and effective construction by which the slight errors in feed of each operation are automatically corrected at the completion of each operation so that all danger of an accumulating error is avoided. 80

I claim:

1. In a machine of the character described, the combination of a feed roll 85 mounted in fixed bearings, a spring pressed frame pivotally mounted adjacent to said fixed feed roll, a second feed roll journaled in said frame, suitable registering means adapted to relatively shift superposed webs 90 into registered position, and means for rocking said frame for simultaneously separating said feed rolls and actuating said registering means.

2. In a machine of the character described, the combination of suitable feeding means, conical registering members, a vertically movable U-shaped frame supporting said registering members, and means for actuating said frame. 95

3. In a machine of the character described, the combination of suitable feeding means, conical registering members, a vertically movable U-shaped rod carrying said registering members, suitable guides in 105 which said U-shaped rod operates, and means for operating said U-shaped rod.

4. In a machine of the character described, the combination of suitable feeding means, conical registering members, a vertically movable U-shaped frame supporting 110 said registering members, a rock arm engaging said frame, and means for actuating said rock-arm.

5. In a machine of the character described, the combination of suitable feeding means, conical registering members, a vertically movable U-shaped frame supporting 115 said registering members, a rock arm engaging said frame, a web cutting device and 120 means actuated by said cutting device for releasing the feeding means from the web and actuating said rock arm.

6. In a machine of the character described, the combination of suitable feeding 125 means, a vertically movable pressure bar adapted to engage and hold a web, a cutter bar carried by said pressure bar and movable relatively thereto, a spring device yielding 130ingly resisting relative movement between

the pressure and cutter bars, and suitable operating means.

7. In a machine of the character described, the combination of suitable feeding means, a vertically movable pressure bar 5 adapted to engage and hold a web, a cutter bar carried by said pressure bar and movable relatively thereto, a spring device yieldingly resisting relative movement between the pressure and cutter bars, suitable 10 registering means, means actuated by said cutter bar for releasing said feeding means

from the web and actuating said registering means, and suitable operating means.

8. In a machine of the character described, the combination of suitable feed rolls, a ratchet drive mechanism suitably geared to said rolls, a rotary crank member carrying a dog which actuates said ratchet mechanism, and an adjustable stop limiting 15 the driving movement of said crank members. 20

HERBERT L. ROBERTS.
